UNITED STATES PATENT OFFICE.

FRANK F. SLOCOMB, OF PHILADELPHIA, PENNSYLVANIA, ASSIGNOR TO F. F. SLOCOMB & CO., INCORPORATED, A CORPORATION OF DELAWARE.

LEATHER-STAKING MACHINE.

1,247,021.

Specification of Letters Patent. Patented Nov. 20, 1917.

Application filed November 6, 1911. Serial No. 658,646.

To all whom it may concern:

Be it known that I, FRANK F. SLOCOMB, a citizen of the United States, residing in the city and county of Philadelphia, State of 5 Pennsylvania, have invented a new and useful Leather-Staking Machine, of which the following is a specification.

My present invention relates to a staking machine and consists of a novel construction 10 and arrangement of the staking tools and their adjuncts.

It further consists of other novel features of construction, all as will hereinafter be fully set forth.

15 For the purpose of illustrating my invention, I have shown in the accompanying drawings, one form thereof which is at present preferred by me, since the same has been found in practice to give satisfactory 20 and reliable results, although it is to be understood that the various instrumentalities of which my invention consists can be variously arranged and organized and that my invention is not limited to the precise arrangement and organization of these instrumentalities as herein shown and described.

Figure 1 represents a sectional elevation of a leather staking machine embodying my invention, a portion of the same being 30 broken away.

Fig. 2 represents a side elevation of the bracket for holding the staking tools.

Fig. 3 represents a front elevation of a staking blade and certain of its adjuncts.

35 Fig. 4 represents a side elevation of one of the brackets employed.

Fig. 5 represents a front elevation partly in section of a staking roll and the bracket in which it is journaled.

40 Fig. 6 represents a perspective view of one of the journals seen in Fig. 5.

Fig. 7 represents a plan view of Fig. 4.

Fig. 8 represents a plan view of the bracket seen in Fig. 5.

45 Fig. 9 represents a front elevation of the bracket seen in Fig. 2.

Similar numerals of reference indicate corresponding parts in the figures.

Referring to the drawings:-

50 1 designates the housing of the machine which may be of any desired construction. 2 designates a connecting rod, a portion of the same being broken away, it being of course understood that said connecting rod

may be actuated or reciprocated by means 55 of a crank or other device (not shown).

3 designates a pin or pivot common to said connecting rod and the plates 4, the general contour of said plates being understood by reference to Fig. 1, said plates when in position forming with their adjuncts, a cross head 5 which reciprocates in suitable slides, and a detailed description of the latter is unnecessary since the same is old in the art.

Pivoted at 6 to the plates 4 is an upper 65 jaw 7, and pivoted at 8 to the plates 4 is the lower jaw 9. The upper jaw 7 has secured thereto in the usual manner, a bracket 10 through which passes a threaded stem 11, which is secured with respect to the bracket 70 by means of suitable nuts 12 and 13. The lower end of the threaded stem 11 is forked, as indicated at 14, in order to receive the journal 15 which is pivoted with respect thereto by means of bolts and nuts 16, or 75 equivalent fastening devices.

17 designates a roller carried by the forked end of the journal 15 and secured therein by means of a bearing pin 18, said roller co-operating with the cam 19 on the connecting 80 rod 2, as will be apparent by reference to Fig. 1. 20 designates rods which are mounted on the pivot pin 3 and extend through a cross bar 21, carried by the bracket 10, and at their upper end they are provided with 85 a plurality of nuts 22 having threaded engagement therewith and one of which serves as a lock nut. 23 is a washer between which and the cross bar 21 is interposed a spring 24, it being understood that two of these 90 rods 20 and their adjuncts are employed.

In order to positively limit the extent of downward movement of the bracket 10 it is desirable in some cases to provide a stop therefor, and I have shown one type of a 95 construction which will accomplish this result. The rod 20 is provided with a shoulder or stop 25 integral therewith or adjustable thereon, so that when the upper jaw 7 rocks on its pivot 6 the downward movement of the bracket 10 will be limited. This limiting of the downward movement of the bracket 10, and thereby the upward movement of the forward end of the upper jaw 7 which carries the rollers may also be obtained by providing a strap 26 which passes over the jaw 7 on the opposite side of the pivotal pin 6 thereof, and is secured to the 100 105

plates 4 of the cross head 5 by means of fastening devices 27. The forward end of the upper jaw 7 is provided with a novel construction of a bracket 28. The bracket 28 is provided at its rear end with one or more slots 29 through which are adapted to pass fastening devices 30, which in the present instance, consist of bolts and nuts, whereby the bracket 28 may be longitudinally adjusted with respect to the forward end of the upper jaw 7. The bracket 28 is provided at its forward end with the guides 31 and the apertures 32, said guides being adapted to coöperate with the bottom portion 10 of a journal 34, and, in the present instance, the guides 31 are shown as being cut away to form parallel guides which co-operate with the parallel sides of the journals 34, whereby said journals may be laterally adjusted and prevented from rotating. The journals 34 are each provided with a conical aperture 35 in which is adapted to be seated a conical bushing 36 in which latter is mounted the shaft 37 of the roller 38. 15 20 25 30 35

39 designates fastening devices which are adapted to pass through the slots 32 in the bracket 28, and have threaded engagement with the journals 34, whereby the journals 34 may be laterally adjusted in order to maintain the proper working fit between the wearing parts and thus overcome any rattling or pounding of the roller 38, such as occurs in devices of this character as heretofore constructed after the parts are in service for some time.

The lower jaw 9 has secured thereto a novel construction of a bracket 41 having its rear portion provided with a plurality of apertures 42 through which the fastening devices 43 pass, whereby said bracket 41 may be longitudinally adjusted with respect to the lower jaw 9. The bracket 41 is provided with the ribs 44 which serve as a guide for the base of a blade 45 which is secured to the bracket by means of a set screw 46, or equivalent fastening device. 47 designates bearing faces. 49 designates a blade supporting bracket to which a staking blade 50 is secured by means of fastening devices 51. The blade supporting bracket 49 is provided with the downwardly extending lugs 52 which are faced off in order to engage the bearing faces 47, as will be best understood by reference to Fig. 3.

55 The bracket 49 is provided with a downwardly extending apertured portion 53 in which is non-rotatably secured in any desired manner, a threaded rod 54 which latter is adapted to pass through the apertured extension 48 of the bracket 41, and to be secured in its adjusted position by means of nuts 55 and 56 which regulate the position of the blade 50 with respect to the roller 38.

57 is a spring suitably secured to the 60 housing and having one end bearing against

the lower jaw 9, whereby the roller 58 will engage with the cam 59 on the connecting rod 2. The roller 58 is mounted in a similar manner to the roller 17, seen in the upper portion of Fig. 1, and a detailed description of such mounting is therefore unnecessary. 60 designates the front roller which is adjustably mounted with respect to the upper jaw 7 in the usual manner, and a detailed description is therefore unnecessary. 61 is a skin to be treated and 62 is a breast roller which is supported in bearings in the forward part of the machine in any desired manner.

The operation will now be readily apparent to those skilled in this art, and is as follows:—

The jaws 7 and 9 when at or near their extreme forward position appear as seen in Fig. 1, the staking blade 50 assuming a position intermediate the rollers 38 and 60. The hide to be staked is placed in position and held between the body of the operator and the breast roller 62, and the rollers 38 and 60, and the blades 45 and 50 are caused to move rearwardly through the medium of the connecting rod 2, and since the hide is held stationary by the operator, it will be apparent that the proper treatment will be imparted thereto during the rearward movement of the rollers 38 and 60, and the blades 45 and 50, the operator or attendant shifting the hide or skin until every portion of the same has been properly treated or staked.

Special attention is directed to certain of the novel features of my present invention. In devices of this character as heretofore constructed, considerable difficulty has arisen owing to the wear of the rollers 17 and 58 with respect to the cams 19 and 59, and since these rollers are ordinarily mounted in stationary bearings, the proper provision has not been made for causing the rollers to properly coöperate with the cam. In my present device it will be seen that the roller 17 is pivotally carried by the threaded stem 11 so that the same may oscillate and accommodate itself to the operative face of the cam 19, so that the roller 17 will at all times engage the operative face of the cam 19 instead of only a portion thereof.

In devices of this character as heretofore constructed, there is a likelihood of the upper jaw bounding upwardly, and since the operator is bending thereover in order to properly manipulate the hide 61, it sometimes happens that the attachment secured to the upper jaw 7 will strike the operator, and in order to positively prevent this, I provide means for limiting the upward movement of the forward end of the jaw 7 which may be accomplished by placing a stop on the rods 20, or another manner in which this can be advantageously accom-

plished is by providing the strap 26 which will limit the upward movement of the forward end of the jaw 7 as is apparent.

In devices of this character wherein the 5 shaft 37 of the roller 38 is mounted in the ordinary type of bearings, it has been practically impossible to overcome the wear of the bearing to prevent the pounding of the roll against the hide, and in my present 10 construction any wear of the bearings may be quickly and readily overcome by loosening one of the fastening devices 39 and laterally adjusting one or both of the journals 34, and owing to the provision of the conical 15 bearing surface the bearing may be properly adjusted without dismantling the machine as is evident.

Attention is also directed to a novel construction of the bracket 28 and the construction 20 of the base of the journals 34 whereby the latter may be laterally adjusted as desired. Attention is also directed to the novel construction of the brackets 41 and 49, it being seen that the lugs 52 of the bracket 25 49 are mounted on the bearing plates 47, so that by manipulation of the nuts 55 and 56, the relative position of the blade 50, carried by the bracket 49 with respect to the rollers 38 and 60 may be readily and 30 quickly adjusted as desired.

Considerable difficulty has arisen in devices of this character wherein two rods are employed, to adjust the relative position of the staking blade 50 with respect to the 35 rollers carried by the upper jaw, since it is very difficult for the ordinary workman to adjust the position of the staking blade 50 so that the same will be in true alinement with the roller, the result of which is that the 40 roller wears conical and as it is impossible to do satisfactory work with a conical roller, it is necessary to frequently true up the roller and then readjust the same. Special 45 attention is directed to the manner in which I have overcome this difficulty, and in my construction the staking blade is always in alinement with the roller, owing to the provision of a single rod and the manner in which the same is mounted, so that the staking 50 blade 50 when adjusted will always be in true alinement with the roller 38, and the liability of the roller 38 wearing conical has been entirely eliminated. Attention 55 is also directed to the fact that the journals 34 are mounted in such a manner that while they are laterally adjustable, the rotation of the same with respect to their support is prevented, so that in the act of adjusting the journals it is impossible to get the roller 60 out of true alinement.

It will now be apparent that I have devised a novel and useful construction of a leather staking machine which embodies the

features of advantage enumerated as desirable in the statement of the invention and 65 the above description, and while I have, in the present instance, shown and described a preferred embodiment thereof which has been found in practice to give satisfactory and reliable results, it is to be understood 70 that the same is susceptible of modification in various particulars without departing from the spirit or scope of the invention or sacrificing any of its advantages.

Having thus described my invention, what 75 I claim as new and desire to secure by Letters Patent, is:—

1. In a leather staking machine, a staking jaw, a bracket secured thereto having a laterally extending guideway, a staking roller 80 having a conical journal and a conical bearing mounted in said guideway for the reception of said journal, whereby said bearing may be adjusted toward or away from said staking roller.

2. In a leather staking machine, an upper jaw, a bracket secured thereto and having guides on the outer portions thereof, conical journal bearings adjustably secured with respect to said guides, and a staking tool 90 having conical journals rotatably mounted in said conical bearings.

3. In a leather staking machine, a lower jaw, a bracket carried thereby and provided with bearing faces and a depending 95 centrally located, apertured lug, a second bracket having lugs seated on said bearing faces, a centrally located rod passing through said central lug and secured to said second bracket, a lower staking tool, secured to said second bracket, and means for longitudinally adjusting said central rod with respect to said first bracket to vary longitudinally the position of said lower staking tool.

4. In a leather staking machine, upper 105 and lower jaws, actuating means therefor, staking devices carried by said upper jaw, a bracket carried by said lower jaw and provided with bearing faces and a depending centrally located apertured lug, a second bracket having lugs seated on said bearing faces, a single centrally located rod passing through said central lug and secured to said second bracket, a lower staking tool secured to said second bracket and located immediately of said staking devices on said upper jaw, and means for adjusting said central rod with respect to said first bracket to vary the relative location of said lower staking 110 tool with respect to said upper staking 115 devices.
